Primary Examiner — Thomas Johannes*Assistant Examiner* — Catherine Ho(74) *Attorney, Agent, or Firm* — Skaar Ulbich Macari, P.A.(57) **CLAIM**

The ornamental design for a glove, as shown and described.

DESCRIPTION

FIG. 1 is a top perspective of a glove showing our new design;
 FIG. 2 is a top plan view thereof;

FIG. 3 is a bottom plan view thereof;

FIG. 4 is a side elevation view thereof;

FIG. 5 is a side elevation view thereof; and,

FIG. 6 is a front perspective view thereof.

The darker dashed broken line shown along the edges of the glove represents stitching that forms part of the claimed design. All other broken lines are included to show environmental elements that forms no part of the claimed design.
